UNITED STATES PATENT OFFICE.

WILLIAM W. BYTHINER, OF PHILADELPHIA, PENNSYLVANIA.

TELEPHONE ATTACHMENT.

No. 884,637.

Specification of Letters Patent.

Patented April 14, 1908.

Application filed September 5, 1907. Serial No. 391,433.

To all whom it may concern:

Be it known that I, WILLIAM W. BYTHINER, a citizen of the United States, residing at Philadelphia, in the county of Philadelphia and State of Pennsylvania, have invented 5 certain new and useful Improvements in a Telephone Attachment, of which the following is a specification.

My invention relates to an attachment for 10 telephones and the object of my invention is to provide a device for holding the plate carrying the number of the telephone, or advertising matter, and also for holding a lead pencil; a further object of my invention is to 15 make the attachment so that it may be readily secured to any telephone and which can be manufactured at a very low cost.

Referring to the drawing: Figure 1 is a perspective view of the transmitter of a telephone instrument, showing my invention attached thereto; Fig. 2 is a front elevation of the attachment with the number plate removed; and Fig. 3 is a side view of Fig. 2.

In the drawing 1 represents the transmitter casing of a telephone instrument, supported on a stand 2. The mouth piece 3 is screwed into the transmitter casing in the usual manner.

My improved attachment is preferably 30 made of wire and consists of an eye 4 adapted to encircle the mouth piece 3. The wire is continued from the eye 4 in either direction and forms the horizontal base 5, of the frame 6 for holding the number plate 7, which latter is secured to the sides of the frame 6 by bending the metal tabs 8 around the sides of the frame 6.

The wires from the vertical frame 6 extend over to the back of the transmitter casing 1 and the depending portions 9 of the said wires 40 form a spring portion for holding the attachment securely upon the transmitter casing.

The holder for the pencil 10 consists of a clamp member 12, formed of the wire, and located above the number plate frame. The clamp member 12 is provided with slightly

curved portions 13 to embrace the pencil 10 and hold it in place when the same is forced between the coils of the clamp member.

The attachment is formed of one continuous piece of wire, one end of which is secured at the point 14 and the other end at the point 15, thus forming a rigid structure.

It will be seen that my attachment may be readily placed upon any telephone by simply 55 removing the mouth piece 3 and inserting the same through the eye 4 of the attachment. The spring portion 9 is placed over the transmitter casing to hold the attachment securely in place. A pen or pencil can be held in the 60 clamp member and a plate for the telephone number, advertising matter or the like may be secured in the vertical frame 6.

Having thus described my invention I claim and desire to secure by Letters Patent. 65

1. In an attachment for telephones, the combination of a wire having a circular portion adapted to encircle the transmitter of a telephone, a spring portion formed of said wire to engage the back of the telephone instrument to hold said attachment in place, vertical members formed in said wire above 70 said eye, a number plate and means for attaching said number plate to said vertical members.

2. In an attachment for telephones, the combination of a wire having a circular portion adapted to encircle the transmitter of a telephone, a spring portion formed of said wire to engage the back of the telephone instrument, a double coil formed in said wire adapted to hold a pencil or the like, vertical members formed in said wire and a number plate adapted to be secured between said vertical members.

In testimony whereof I have affixed my signature in presence of two witnesses.

WILLIAM W. BYTHINER.
